CLAIM

The ornamental design for a contact lens storage case, as shown and described.

DESCRIPTION

FIG. 1 is a perspective right, front, and top view of a first embodiment of a contact lens storage case with a forward-facing valve-vent, depicting the lids in a closed position, showing my new design.

FIG. 2 is a perspective right, front, and top view of the contact lens storage case of FIG. 1 with the lids in an open position.

FIG. 3 is a perspective right, top, and rear view of the contact lens storage case of FIG. 1 with the lids in an open position. FIG. 4 is a front elevation view of the contact lens storage case shown in FIG. 1 with the lids in a closed position.

FIG. 5 a front elevation view of the contact lens storage case shown in FIG. 1 with the lids in an open position.

FIG. 6 is a perspective right, front, and rear view of the contact lens storage case of FIG. 1 with the lids in a closed position.

FIG. 7 is a top plan view of the contact lens storage case of FIG. 1 with the lids in a closed position.

FIG. 8 is a top plan view of the contact lens storage case of FIG. 1 with the lids in an open position.

FIG. 9 is a bottom plan view of the contact lens storage case of FIG. 1 with the lids in a closed position.

FIG. 10 is a bottom plan view of the contact lens storage case of FIG. 1 with the lids in an open position.

FIG. 11 is a rear elevation view of the contact lens storage case of FIG. 1 with the lids in a closed position.

FIG. 12 is a rear elevation view of the contact lens storage case of FIG. 1 with the lids in an open position.

FIG. 13 is a right side elevation view of the contact lens storage case of FIG. 1 with the lids in a closed position, the left side being a mirror image of the right.

FIG. 14 is a right side elevation view of the contact lens storage case of FIG. 1 with the lids in an open position, the left side being a mirror image of the right.

FIG. 15 is a perspective right, front, and top view of another embodiment of a contact lens storage case with a rearward-facing valve-vent, and depicting the lids in a closed position, showing my new design.

FIG. 16 is a perspective right, front, and top view of the contact lens storage case of FIG. 15 with the lids in an open position.

FIG. 17 is a perspective right, top, and rear view of the contact lens storage case of FIG. 15 with the lids in an open position.

FIG. 18 is a rear elevation view of the contact lens storage case of FIG. 15 with the lids in a closed position.

(Continued)

FIG. 19 is a rear elevation view of the contact lens storage case of FIG. 15 with the lids in an open position.

FIG. 20 is a perspective right, front, and rear view of the contact lens storage case of FIG. 15 with the lids in a closed position.

FIG. 21 is a top plan view of the contact lens storage case of FIG. 15 with the lids in a closed position.

FIG. 22 is a top plan view of the contact lens storage case of FIG. 15 with the lids in an open position.

FIG. 23 is a bottom plan view of the contact lens storage case of FIG. 15 with the lids in a closed position.

FIG. 24 is a bottom plan view of the contact lens storage case of FIG. 15 with the lids in an open position.

FIG. 25 is a front elevation view of the contact lens storage case shown in FIG. 15 with the lids in a closed position.

FIG. 26 a front elevation view of the contact lens storage case shown in FIG. 15 with the lids in an open position.

FIG. 27 is a right side elevation view of the contact lens storage case of FIG. 15 with the lids in a closed position, the left side being a mirror image of the right; and,

FIG. 28 is a right side elevation view of the contact lens storage case of FIG. 15 with the lids in an open position, the left side being a mirror image of the right.

The broken lines depict portions of the contact lens storage case that form no part of the claimed design.
